UNITED STATES PATENT OFFICE.

WILLIAM H. SAUVAGE, OF NEW YORK, N. Y., ASSIGNOR, BY MESNE ASSIGNMENTS,
TO THE GOULD COUPLER COMPANY, A CORPORATION OF MARYLAND.

SLACK ADJUSTER.

Application filed April 24, 1922. Serial No. 556,201.

To all whom it may concern:

Be it known that I, WILLIAM H. SAUVAGE, a citizen of the United States, residing at New York, in the county of New York and 5 State of New York, have invented new and useful Improvements in Slack Adjusters, of which the following is a specification.

This invention relates to improvements in slack adjusters and more particularly to 10 automatically operating slack adjusters for railway brake rigging for regulating the relative or effective length of the tension or compression member thereof.

One of the objects of the present invention is to provide a simple and reliable 15 mechanism for automatically regulating the tension or compression member connected with either the foundation brake rigging beneath the car floor or the truck brake rig-

20 ging. A further object is to provide a durable and strong mechanism of the above character for automatically regulating the brake rigging, thereby to ensure predetermined and uniform piston travel or hand 25 brake operation.

A further object is to provide a practical and efficient device of the above general 30 character which may be easily and quickly applied to any standard equipment now in use without material modification of the remaining parts.

A further object is to provide an inexpensive mechanism of the above character 35 having relatively few parts, which are automatic in action and as nearly "fool proof" as possible.

A further object is to provide a mechanism of the above character which will 40 eliminate the necessity of any manual operation or adjustment and be entirely automatic in its operation except when replacement of brake shoes or wheels becomes necessary, at which time the mechanism is 45 reset.

Other objects will be in part obvious and in part hereinafter pointed out in connection with the following analysis of the invention when taken in connection with the 50 accompanying sheets of drawings illustrating several of various possible embodiments of the invention and wherein corresponding parts are denoted by similar reference characters.

55 In these drawings,

Figure 1 is an elevational view of such parts of a brake rigging as are necessary to understand the present invention as applied thereto;

Figure 2 is a similar view showing the 60 same parts in actuated position with excess travel about to be taken up;

Figure 3 is a plan view of a modification showing the invention as applied to the 65 foundation brake rigging;

Figure 4 is an elevational view showing another modification with the invention applied to a brake beam strut;

Figure 5 is a side elevational view of a 70 live lever and brake beam strut in modified form;

Figure 6 is a view similar to Figure 5, showing a further modification of similar parts;

Figure 7 is a view similar to Figure 1, 75 with the slack adjuster connecting live and dead levers intermediate their ends;

Figure 8 is a side elevation showing the 80 slack adjuster mechanism applied to outside hung brake beams.

Referring now to the drawings in detail and more particularly to Figure 1, there is shown a live lever 12 and a dead lever 13 at opposite sides of a truck bolster 14. The lower ends of the live and dead lever are 85 connected by means of a compression member which preferably consists of two flat bars 15 secured together intermediate their ends and between which flat bars the lower ends of the live and dead levers are 90 secured. These bars 15 at one end are provided with a horizontal slot 16 through which a pin 17 is adapted to pass for movably securing the lower end of the live lever thereto. This pin 17 is adapted to travel 95 along the slot 16 in the manner and under the conditions hereinafter explained for taking up and holding the slack in the brake rigging. This pin 17 also supports the lower end of a bifurcated pawl 18 having a tooth 20 adapted to engage ratchet means preferably in the form of teeth 21 on the upper surfaces of the bars 15.

Intermediate the ends of both the live and dead levers are pivotally secured at 22, 105 brake beam struts 23 provided with brake shoe heads 24 carrying the brake shoes 25, these parts being supported by hangers 26. Intermediate the pins 17 and 22 is a second gravity actuated pawl 27, adapted also to 110

contact with the ratchet teeth 21. The upper end of the live lever is provided with the pull rod 28 for moving the live lever within the guide rod 30 secured to the truck bolster. A stop pin 31 may be provided if desired for limiting the rearward or release movement of the live lever, if normally hung too far from the bottom for this to perform the stop function.

The stop pin 31 on the live lever guide 30 is desirable in cases where the live lever normally keeps a position several inches away from the truck bolster in full release position. For illustration, assume that the car is properly adjusted with the upper end of the live lever 6 inches away from the bolster. Should the live lever now be forced all of the way back against the bolster by any means, were it not for the live lever guide and stop, an extra tooth might be taken up on the ratchet 21 and at the same time the live lever, through the pull rod connections, would pull the live lever on the truck at the other end of the car a corresponding distance away from the bolster, thus reducing the predetermined brake shoe clearance required and at the same time shorten the piston travel less than normal, thereby decreasing the efficiency of the braking apparatus. With the construction here illustrated, this unnatural condition cannot occur.

The rack-bars, live and dead levers, on freight trucks are usually set at an angle of approximately 40° , as shown in Figure 1, but in passenger equipment and on electric and Pullman cars the levers generally occupy a vertical position. For convenience of illustration the invention in its other various modifications will be hereinafter shown in this vertical position.

In the operation of this device the parts occupy the normal or released position shown in Figure 1, and the actuated position shown in Figure 2, when excess slack is being taken up. When the brakes are applied, the upper end of the live lever is moved relatively towards the left and the bar 15 connecting the lower end of the dead lever is moved relatively towards the right, thus bringing the brake shoes into engagement with the peripheries of the wheels. During the application of the brakes, the main holding pawl 20 coacting with the ratchet 21 will lock fast to the compression ratchet bars 15 and prevent any relative movement between the lower end of the live lever and the bar 15. If, however, the normal piston travel, for example, is exceeded on or during the application of the brakes, then the pawl 27 is drawn over one tooth of the rack 21 and drops into the next tooth, as shown in Figure 2, whereupon the brakes are released and the parts through their own weight, or return springs,

return to normal position. The pivot pin 29 of the pawl 27 acts as a fulcrum and the holding pawl tooth 20 is moved relatively towards the left one notch, thus permanently taking up the wear or lost motion temporarily taken up on application by pawl 27, which allows the live lever to return to its normal position. The next application of the brakes to the wheel does not permit the pawl 27 to engage another notch until the wheels, brake shoes or other parts wear to a sufficient extent to permit another notch to be taken up. This progressive take-up action occurs as often as any excess travel or movement of the pawl 27 permits.

The connector bar 15 may be provided with extra holes 32, if desired, whereby a longer or shorter initial connection between the live and dead levers is permitted.

When it is desired to shorten the compression member 15, as is necessary when replacing worn shoes or wheels, the inspector merely disengages both pawls 20 and 27 and through gravity of all the parts move towards the right of the slot 16, whereupon the pawls are permitted to drop into their operative position and the apparatus is again ready for use.

In Figure 3 there is shown a similar type of slack adjuster mechanism applied to the foundation brake rigging beneath the car floor. In this view, a tension bar 40 is interposed between the central part of a live lever 41 and a dead lever 42, one end of the live lever being connected at 43 to a piston 44 of a cylinder 45, and the corresponding end of the dead lever 42 being pivotally connected at 46 to the opposite end of the cylinder. The opposite ends of the live and dead levers are provided with pull rods 47 connected with the truck brake rigging. One edge of the tension rod 40 is provided with a rack 48 adapted to be engaged by holding pawl 50 and take-up pawl 51 pivoted at 52 to the live lever. A slot 53 is provided in the tension rods 40 to permit relative movement of the fulcrum pin of the pawl 50 towards the right as wear of the parts takes place. A spring 54 reacts between the pawls in a manner to normally hold the pawls in engagement with the ratchet teeth. In this form the levers lie in a horizontal position and in order to ensure proper operation and engagement of the pawls, at all times the compression spring is used as shown.

The operation of this device is substantially the same as that above described in connection with Figures 1 and 2, that is, when the cylinder piston moves relatively outward or to the left, if excess travel takes place, then pawl 51 slips over a tooth and on return of the parts to normal position the pin 52 acts as a fulcrum and causes

the holding pawl 50 to take up another notch on the compression bar as the parts return to normal position.

In Figure 4, there is shown this same type 5 of slack adjuster applied directly to the brake beam strut. This strut 56 is provided with a ratchet 57 on its underside adapted to be engaged by a take-up pawl 58 mounted upon the live lever 60. On 10 the fulcrum point 61 is pivotally secured a second pawl 62 provided with a tooth 63 co-acting with this same ratchet. The opposite end of the pawl is preferably weighted, as indicated at 64, whereby to 15 ensure proper engagement at all times. This device operates in the same manner as the previous form.

In Figure 5, there is shown the same 20 general type of mechanism, that is, the brake beam strut 66 is provided with a ratchet 67 on its upper surface adapted to be engaged by take-up pawl 68, and a holding pawl 70 carried by the live lever 71, on excess travel.

25 Figure 6 shows a further modification with the slack adjuster applied to the brake beam strut, but in this case the strut is provided with ratchet means in the form of racks 72 and 73 on both its upper and lower surfaces. The permanent take-up and holding pawl 74 engages the upper rack while the temporary take-up pawl 75 engages the lower rack, this pawl 75 being weighted at 76, to ensure proper engagement. The operation is the same as above described.

Figure 7 shows a different type of truck 40 brake rigging, that is, the live and dead levers 80 and 81 are provided with a tension member 82 pivotally connecting them between their ends. This tension member is provided with ratchets 83 and 84 on the upper and lower surfaces adapted to be engaged by pawls 85 and 86, respectively, in the same manner as shown in Figure 6, 45 which parts operate substantially as above described.

Figure 8 illustrates a further type of truck 50 brake rigging, generally known as outside hung brake beams, that is, the wheels are between the live and dead levers 90 and 91 respectively. A tension member 92 connects the lower ends of these levers and is provided with a ratchet 93 adapted to be engaged by a permanent take-up pawl 94 and a temporary take-up pawl 95. As pull rod 96 is moved towards the right, the reaction between the parts take place to move the truck brake beams toward each other. Any excess travel is temporarily taken up 55 by the pawl 95 and on release of the brakes the holding pawl 94 moves over another tooth and holds the parts in the same locked position. The operation is substantially as that above described.

60 In nearly all of these modifications the

take-up pawl is attached to the live lever between the brake beam fulcrum and the bottom rod connection, which allows predetermined brake shoe clearance at all times, whereas if this take-up pawl were 70 attached to the center line on the live lever pin a predetermined brake shoe clearance would only be problematical and uncertain.

75 While the present invention is shown as applied primarily to car trucks, cylinders and brake beam struts, requiring only a single adjuster to the cylinder levers, it can be readily understood that the brake lever connections will work with or without the cylinder lever connection or together or each 80 alone in any part of the brake rigging when automatic adjustment is desired with or without brake beams and is operative with either hand brakes or both or in vehicles employing brakes, and I, therefore, do not 85 wish to be limited to any one or all of the various modifications shown and described.

85 It will be understood from the above that the present invention is of a simple and practical construction, reliable and efficient 90 in use and operation, is inexpensive to manufacture and assemble, and without material modification can replace the present tension or compression member now in brake rigging without in any way affecting the other 95 working parts.

95 It will thus be seen that the present invention provides a simple and practical slack adjuster mechanism in which the adjusting rod and take-up rod are combined in one, 100 thus simplifying the mechanism as a whole and reducing the number of parts to be manufactured and assembled. In short, the invention is believed to accomplish, among others, all of the objects and advantages 105 herein set forth.

I claim:

1. In a slack adjuster, in combination with a live lever and a compression member of brake rigging, said compression member comprising a plurality of bars in spaced relation, said live lever having its lower end disposed intermediate said bars, said bars adjacent the latter end having lateral slots therethrough, ratchet teeth on a lateral surface of said bars, a bifurcated pawl straddling said bars having its bridge constituting a tooth and engaging said ratchet teeth, a pin passing through said slots and pivotally connecting said live lever and pawl, and a pawl pivoted to the live lever at one side of the bars and engaging said ratchet teeth on the side of the live lever opposite to that of the first mentioned pawl. 110

115 2. In a slack adjuster, in combination with a live lever and a compression member of brake rigging, said compression member having a lateral slot therethrough, the lower end of the live lever being disposed opposite said slot, a bifurcated pawl straddling said 120

125

compression member, a pin passing through said slot and connecting said end and the arms of said pawl, the bridge of said pawl constituting a tooth, ratchet teeth on said compression member engaged by said tooth, and a pawl pivoted to the live lever at a different elevation from the first mentioned

pawl and engaging said ratchet teeth on the side of the live lever opposite to that of said first mentioned pawl.

10

In witness whereof I have hereunto set my hand this 10th day of April, 1922.

WILLIAM H. SAUVAGE.
